DISPLAY FOLDER

Thomas W. Foster, Chicago, Ill., assignor to Container Corporation of America, Chicago, Ill., a corporation of Delaware

Application March 22, 1952, Serial No. 278,010

1 Claim. (Cl. 40—155)

1

The present invention relates to display folders and more particularly to an improved folder which may be formed from folding carton stock or other paperboard material and which is designed for use as a display rack or holder for displaying articles of flat sheet form as for example cellulose ester transfer prints commonly known as decalcomania or simply "decals," wall paper or fabric samples, photographs, decorative prints and the like. It is among the principal objects of the present invention to provide an improved folder of this character which may initially be constructed in the form of a flat blank of one-piece unitary construction capable of readily being folded about the article to be displayed and which, when so assembled thereon, will provide an attractive frame-like border for the article while at the same time affording rigidity for the edge portions of the article.

Another object of the invention is to provide a display folder of this character which requires the use of a relatively small amount of the paperboard material for its construction thereby effecting economy of material in the large scale manufacture of the article.

A further object of the invention is to provide a display folder for articles in sheet form which may be easily applied to the articles so as to contain the articles therein by the simple expedient of performing a relatively few folding and tucking operations.

A still further object of the invention is to provide such a display folder which will effectively contain the article to be displayed while at the same time permitting easy removal of the article when desired.

An additional object of the invention is to provide a display folder for articles in sheet form which, when assembled upon the article to contain the same therein is itself of a relatively flat nature having slight thickness so that a number of the thus packaged articles may be stacked together in a small space with the folder affording the necessary rigidity to the packaged article to enable ready "thumbing" through the stack for selection of a particular article without the danger of tearing or otherwise mutilating or soiling of the edges of the article.

The improved display folder embodying the present invention is particularly well adapted for use in the displaying and marketing of decals and similar articles of sheet form and to this end it contemplates the provision of a flat blank preferably of folding carton stock which may be folded about three edge portions of the rectan-

gular flat decal in such a manner as to provide a partial border extending around three sides of the decal and which may also be folded upon itself in such a manner as to retain securely the folder in its position of use. If desired a rigid backing sheet and a protective transparent facing sheet for the decal may also be included in the assembly so that the thus packaged decal although visible for purposes of display is entirely enclosed and protected against damage or soiling.

The provision of a display folder which is attractive in its appearance; one which is comprised of a small amount of paperboard material and still which is rugged and durable and which consequently will withstand rough usage; one which provides a border effect for the article to be displayed and at the same time which affords visibility of a major portion of the packaged article; and one which otherwise is well adapted to perform the services required of it, are further desirable features that have been borne in mind in the production and development of the present invention.

Other objects and advantages of the invention not particularly enumerated above will become more readily apparent as the nature of the invention is better understood.

In the accompanying single sheet of drawings forming a part of this specification, one embodiment of the invention has been shown.

In these drawings:

Fig. 1 is a plan view of a blank from which the improved display container comprising the present invention may be folded;

Fig. 2 is a rear view of the folder set up for use and showing an article contained therein; and

Fig. 3 is an enlarged rear perspective view of the folder in a partially folded condition, illustrating the manner in which progressive folding and tucking operations are performed in producing the finished folder. In this view certain parts have been broken away more clearly to reveal the nature of the invention.

A preferred form of the invention has been shown in the drawings and will be described herein, but it should be understood that the invention is not limited to the specific disclosure made, and that the appended claim should be construed as broadly as the prior art will permit.

Referring now to the drawings in detail and in particular to Fig. 1, the improved display folder is formed from a single sheet 10 of folding carton stock or other paperboard material to pro-

vide a plurality of connected sections or panels which are set off by fold lines which may be in the form of creases or scoring, all of which have been indicated in dotted lines and which serve to separate the blank into its various component parts.

An understanding of the nature of the folded display device and its application to an article which is contained therein for display purposes will in a large manner facilitate an understanding of the parts of the blank 10 and the manner in which it may be folded to produce the completed display assembly. Accordingly, as shown in Figs. 2 and 3, the erected display folder involves in its general organization a generally U-shaped frame-like structure having upper and lower parallel leg portions 12 and 14 and an interconnecting base portion 16. The three portions 12, 14 and 16 are generally of inwardly presented channel-shape cross section and the channel regions thereof are adapted to straddle the upper, lower, and one side border portion of a composite article as for example a decal display assembly such as the decal proper 18, a stiffener or backing sheet 20 and a transparent protective window or facing sheet 22 such as are shown in Fig. 2.

Without reference to the details of the folder construction as exemplified by the blank of Fig. 1, the erected folder structure as shown in Fig. 3 includes a composite back border wall of suitable U-shape configuration conforming to the overall shape of the folder as a whole, a similarly shaped front border wall spaced from the back wall a slight distance so as to permit reception of the border portions of the article to be displayed therebetween, and interconnecting narrow top, bottom and end walls. The front wall is substantially continuous as are also the narrow individual interconnecting walls at the top, bottom and side of the structure but the rear wall is of a composite nature consisting as it does of from one to four layers of the paperboard material in various portions thereof as will be pointed out presently.

Referring now to Fig. 1, the blank 10 includes a panel section 24 of generally U-shaped outline which is separated from the remainder of the blank by means of a transverse fold line 26, upper and lower longitudinal fold lines 28 and 30, and aligned short transverse fold lines 32 and 34. As will become clear presently, the panel 24 constitutes the front side of the display folder and is adapted to overlie the marginal portions of the article to be displayed on three sides thereof. To enhance the border effect, the parallel sides of the panel 24 may merge with the base thereof by means of curved corner portions 36.

A pair of similar outwardly offset extensions designated in their entirety at 38 and 40 are provided along the upper and lower edge of the panel 24 and each of these extensions is divided into a relatively narrow elongated panel section 42 and a generally trapezoidal-shaped panel section 44 by means of an intervening fold line 46 extending parallel to the fold line 30. A third panel section 48 which constitutes a tuck flap in the completely erected structure is rendered readily bendable for tucking purposes by means of a plurality of crease lines 50 of which two have been shown for illustrative purposes.

A second U-shaped panel section 52 of lesser U-depth than the panel section 24 is separated from this latter panel section by an intermediate elongated narrow transversely extending panel sec-

tion 54. The panel section 54 is separated from the panel section 24 by means of a transverse fold line 56 and from the panel section 52 by means of a parallel fold line 58. The U-shaped panel section 52 includes a pair of parallel extending leg portions 60 and 62 and a connecting base portion 64. The base portion 64 forms a portion of the composite back wall of the frame-like display folder and the leg portions 60 and 62 likewise constitute portions of the composite back wall and, in addition, each constitutes one element of an interlocking strut assembly associated with this back wall structure. The leg portions 60 and 62 are designed for interlocking cooperation with a pair of similar leg portions 66 and 68 which, in the blank 10, are in the form of panel sections which are separated from the panel section 24 by relatively small narrow transversely extending panel sections 70 and 72. The panel sections 70 and 72 are separated from the panel section 24 by the previously mentioned fold lines 32 and 34, while these aligned panel sections are separated from the panel sections 66 and 68 by fold lines 74 and 76. The outer ends of the leg portions 60 and 62 are provided with locking tongues 78 designed for interlocking engagement with similar locking tongues 80 provided at the outer ends of the panel sections 66 and 68 respectively.

In Fig. 2 the display folder is shown as being operatively applied to a decal package assembly including the decal sheet proper 18, its stiffener or backing sheet 20 and the transparent protective sheet 22 through which the decal pattern may be viewed in the display assembly. It will be understood, of course, that the display folder will be also useful for containing and displaying other articles of a flat nature with or without the use of a backing sheet.

In assembling the decal display of Fig. 2, a blank 10 is placed upon a flat surface so that it will assume the general position shown in Fig. 1 and the front transparent sheet 22, which may be formed of cellulose acetate, is placed thereupon with three adjacent edges thereof in coextensive alignment with the fold lines 30, 56 and 42 and with the other edge in register with the score lines 32 and 38. The decal proper 18 is superimposed on the sheet 22 face down and the backing sheet 20 is placed over the back face of the decal assembly. The blank is then folded along the score line 56 so that the panel section 54 extends at right angles to the plane of the blank and so that the panel section 52 is reversed upon the blank to overlie the panel section 24 with the decal assembly 18, 20, 22 interposed therebetween. The blank is further folded about the score lines 32 and 34 and about the score lines 74 and 76 to bring the panels 66 and 68 across the face of the decal assembly so that the tongues 80 overlie the tongues 78 of the panel sections 60 and 62. The cooperating tongues may then be interlocked with the tongues 80 underlying the tongues 78 and with the leg portions produced by the panel sections 60, 66 and 62, 68 in end to end alignment. The leg portions when thus interlocked constitute strap-like extensions that overlie the upper and lower edge regions of the decal assembly and firmly hold the latter in position of the panel section 24.

The offset extensions 38 and 40 are then folded upwardly out of the plane of the blank about the fold lines 28 and 30 respectively and each extension is then folded about its fold line 46 so that the panel section 38 thereof overlies

one of the interlocked pairs of leg portions 60, 66 or 62, 68 as the case may be.

Prior to movement of the panel sections 38 and 44 to their final positions of parallelism with the plane of the blank, the tuck flaps 48 are bent into a generally curved condition and the ends of the flap are inserted into the spaces existing between the inside faces of the panel sections 38 and 44 and the back face of the reinforcing sheet 20, with the flaps extending behind leg panels. This insertion of the tuck flaps may be performed by a progressive sliding of the flaps into the space provided for them with the operator utilizing four fingers of each hand to slide the flaps into place and with these four fingers opposing the thumb in gripping relationship on the upper and lower parallel leg portions 12 and 14 (Fig. 3) of the display folder.

The display folder is thus completely erected with the decal display assembly contained therein and, in its erected condition, it will be noted that the panel sections 42, constitute elongated narrow top and bottom walls of the folder while the panel section 54 constitutes an elongated narrow side wall therefor. The two small panel sections 70 and 72 constitute fragmentary vertical side walls in the erected structure. The panel section 24 constitutes the front wall of the folder while the panel sections 52 and 38, as well as the interlocking panel sections 60, 66 and 62, 68, and the tucking flaps 48, all constitute a composite back wall for the folder.

The consumer in removing the decal assembly from the display folder preparatory to use may reverse the folding process if desired, thus enabling him to preserve the folder for further use as for example in the case of multiple transfer prints which are applied on a single decal sheet where only one print is to be employed at a particular time. If, however, the consumer is not interested in preserving the folder, he may manually spread the leg portions 12 and 14 apart to expose the edges of the decal assembly and the assembly may then be withdrawn from the folder and the thus distorted folder discarded.

The invention is not to be considered as limited to the exact arrangement of parts shown in the accompanying drawings or described in this

specification as various changes in the details of construction may be resorted to without departing from the spirit of the invention. Only insofar as the invention has particularly been pointed out in the accompanying claim is the same to be limited.

I claim:

A display folder for containing and displaying flat rectangular sheet-like articles comprising a frame-like member formed from a single sheet of folding carton stock and including a front wall panel adapted to overlie the marginal edge portions of the article on three sides thereof, top and bottom panels and a side panel extending laterally from said front panel and adapted to confine the edges of the articles at said sides within the frame-like member, additional side panels extending laterally from said front panel and adapted to confine the edge of the article at the remaining side thereof within the frame-like member, and a rear wall substantially coextensive with said front wall panel and spaced a slight distance from the latter, said rear wall including two pairs of interlocking leg panels extending laterally from opposed side panels and underlying the upper and lower marginal edge portions respectively of the article, a pair of extensions on said top and bottom panels respectively and overlying the respective pairs of interlocking leg portions, and a tuck flap extending from each extension for reception in the space between the respective interlocked leg portions and the opposed portions of said front panel, said tuck flaps each being provided with crease lines extending thereacross to effectively lessen the rigidity of the flap and facilitate insertion of the latter into the spaces provided for it.

THOMAS W. FOSTER.
